7 Claims. (Cl. 196—52)

1

This invention relates to the catalytic conversion of hydrocarbons under cracking conditions using a solid cracking catalyst, and is particularly concerned with the maintenance of the cracking catalyst at an efficient level of catalytic activity.

In the catalytic conversion of hydrocarbons under cracking conditions, hereafter referred to as catalytic cracking, the original hydrocarbons are converted to hydrocarbons of different molecular weight or structure or both by contact with a cracking catalyst, which directs and accelerates the cracking reaction and concomitantly accumulates a deposit of hydrocarbonaceous material commonly referred to as coke. Since the accumulation of such a deposit on the catalyst diminishes its efficiency and since this effect increases as the amount of the deposit increases, it is the common practice in moving catalyst systems to continue the cracking or on-stream period until the catalyst accumulates a deposit of coke which contains carbon to the total amount of about 10 to 20 grams per liter of catalyst. (Since the carbon content is conveniently determined, the amount of the coke deposit is generally, as it is herein, referred to its carbon content; as herein used, the amount of the coke deposit is expressed as grams of carbon per liter of contact mass which has been abbreviated to grams per liter.)

When the catalyst is employed as a static bed cooled by indirect heat exchange, the total amount of the coke accumulated is generally somewhat less, usually being of the order of 5 to 10 grams per liter. Thereafter, the catalyst is treated to remove the majority of the deposit on the catalyst by combustion during a regeneration period by contacting the coked catalyst with an oxidizing gas. Due to the difficulty of removing the last portion of the deposit, the catalyst is generally not completely regenerated. After the termination of the regeneration period, the catalyst, in commercial practice, generally has a deposit of less than 1 to 3 grams per liter for moving catalyst systems and about the same amount for the above type of static bed operation. Under these conditions, the catalyst is sufficiently restored to an efficient level of activity as to be ready for reuse in the cracking operation.

The cracking catalysts commercially available for use in the cycle of operations described above have certain properties such that there is only a gradual loss in catalytic activity under the moderate conditions commonly employed in

2

the various phases of the cracking process. If, however, these catalysts are subjected to an atmosphere containing steam, a considerable loss in catalytic activity occurs, the extent of the loss in activity depending, for a given temperature and length of exposure, on the partial pressure of the steam. Since steam is frequently used to aid in the volatilization of high boiling hydrocarbon fractions and hence is present during the cracking period, and is commonly used to strip or purge volatile hydrocarbons from the catalyst prior to regeneration, most catalysts are slowly deteriorated or aged in use during the cracking and purging periods and must be replaced with fresh catalyst when the activity has dropped to an inefficient level. Aging of cracking catalysts is also caused by the steam formed in the combustion of the hydrocarbonaceous deposit or coke which consists essentially of carbon and hydrogen (a typical deposit contains about 5 to 8 weight per cent of hydrogen with the remainder essentially carbon) associated in the form of compounds which are of undetermined composition and which are non-volatile with steam stripping at temperatures of the order of 600° to 1000° F. Combustion of such a deposit produces flue gases which contain, particularly in the early stages of the combustion of the deposit when preferential combustion of the hydrogen of the deposit occurs, an amount of steam sufficient, at the elevated temperatures of combustion, to lower the activity of the catalyst to economically undesirable levels, this effect being particularly noticeable at temperatures above 1200° F. In addition to the steam produced by combustion, steam may be present in the flue gases due to the desorption of water adsorbed during the cracking or purging periods, this effect being particularly noticeable when clay cracking catalysts are used. For this reason, it has been the previous practice to limit the temperatures at which regeneration is conducted to 1100° F. or lower, and even to 1000° F. and lower, during the combustion of the first third of deposit when the concentration of steam in the flue gas may be of the order of 10 to 20 volume per cent.

It has been found, in accordance with the present invention, that cracking catalysts which are used in cyclic cracking operations comprising a regeneration and a cracking period may be protected against the deleterious effect of deactivating partial pressures of steam at elevated temperatures, such as temperatures above 800° F., by maintaining a substantial amount of coke

on said catalyst such as amounts in excess of 10 grams per liter, during the periods in the cyclic cracking operation when the catalyst is contacted with steam.

In one embodiment of the present invention, a cracking catalyst having a deposit of coke thereon is regenerated at temperatures above 1200° F., such as temperatures in the range of 1200° to 1350° F., without substantial loss in activity by contacting such a catalyst with an oxidizing gas under combustion conditions, said catalyst having been subjected to prior process conditions such that sufficient coke, such as amounts in excess of 15 grams per liter, has been deposited on the catalyst as to maintain a protective amount of said coke on said catalyst during those portions of the regeneration period when deactivating partial pressures of steam are present. Since the deactivating effect of the steam depends, among other variables, on the temperature of the operation and partial pressures of 0.1 pound per square inch or lower can deactivate at temperatures of 1200° F. and higher, it is preferred to protect the catalyst by a minimum amount of coke which varies according to the temperature of the operation as hereinafter described. Research has indicated that, by operating the cracking operation under conditions such that the total amount of coke present on the catalyst at the start of regeneration is higher than that formerly used, the regeneration may be effected at higher temperatures than previously thought desirable. The increase in the temperature of regeneration has many important advantages, among which is a greatly increased rate of combustion as well as a lower evolution of heat and decreased amounts of oxidizing gas needed for the same amount of carbon removed, the latter effect being due to an increase in the ratio of carbon monoxide to carbon dioxide in the flue gas. These advantages may be realized in a preferred embodiment of the present invention, in which the amount of coke on the catalyst at the start of a combustion effected at substantially atmospheric pressure and at temperatures of 1200° F. or higher is 30 grams per liter or higher and the catalyst accordingly protected in the presence of the partial pressures of steam in the initial stages of combustion (about 1.5 to 3.0 or even as much as 4.5 pounds per square inch). As the regeneration proceeds, the amount of coke deposit, and hence its protective effect, is reduced but the concentration of steam in the flue gases decreases relatively more rapidly. Thus, although the concentration of steam in the flue gases (due to combustion of the coke deposit) may be as high as 15 or 20 or occasionally as much as about 30 volume per cent during the first third of a regeneration effected in connection with a stable cyclic operation, it is generally lower than 5 to 8 volume per cent during second third of the regeneration. However, it has been found that the deactivating effect of gases having concentrations of steam of even 5 volume per cent (about 0.8 pound per square inch partial pressure of steam) is appreciable at 1200° F. if the period of exposure is sufficiently extended and it is therefore preferred to maintain a protective deposit, such as an amount greater than 15 grams per liter, on the catalyst during regenerations at 1200° F. and higher until the partial pressure of steam in the flue gas is less than about 0.8 pound per square inch. Since investigation has shown that 15 to 20 grams per liter of the hydrocarbonaceous deposit protects

commercial cracking catalysts against the deactivating effect of steam at 1200° F. at least as much as does 6 to 8 grams per liter at 1050° F., the advantages of a regeneration effected at the higher temperature may be maintained even in the later stages of a regeneration of a catalyst initially having a deposit amounting to at least 30 grams per liter without sacrificing the activity of the catalyst.

In another embodiment of the invention, the deactivating effect of steam used in the cracking period is minimized by maintaining a protective deposit on the catalyst during this period. This may be accomplished by incompletely regenerating the catalyst and leaving a residual deposit sufficient to protect the catalyst in the subsequent operations, a particularly effective amount being in excess of about 10 grams per liter. It has been found that, when steam is present in deactivating amounts, the advantages gained by the protective effect of deposits of coke in excess of 10 to 15 grams per liter more than offsets any loss in the cracking activity of catalysts having such deposits. Furthermore, as the amount of coke on a cracking catalyst is increased above about 20 to 25 grams per liter, additional reduction in cracking activity is at a reduced rate whereas the protective effect of such deposits in regard to the deactivating effect of steam continues to increase. Moreover, the loss in cracking activity due to the deposit of coke on the catalyst may be counteracted by increasing the severity of the cracking conditions (increasing the temperature or pressure or decreasing the space velocity and the like) or by the use of a very active catalyst such as a catalyst which, without the deposit of coke, would overcrack the charge stock, and produce excessive quantities of gas and coke.

For example, in cracking operations involving the contact of a catalyst with hydrocarbons admixed with deactivating amounts of steam, such as amounts between 5 to 20 parts by weight of steam to 100 parts of hydrocarbons, at temperatures of 950 to 1100° F., the pressure of the operation being approximately atmospheric (these conditions correspond to about 6.0 to 10.0 pounds per square inch partial pressure of steam for most hydrocarbon charge stocks), it is preferred to subject the catalyst to prior operating conditions, such as prior contact with hydrocarbons or prior partial regeneration, so that at least 15 grams per liter of coke is initially on the catalyst when it is contacted with such deactivating amounts of steam. Larger initial amounts of coke are preferred for the higher concentrations of steam or higher temperatures of cracking or both. Where lower temperatures, such as 800 to 950° F. are employed in the cracking operation, a minimum deposit of the order of 10 grams per liter will be effective.

The cracking catalysts which are adapted for use in the present invention are, in general, those known to the art. Typical cracking catalysts are siliceous contact masses processed so as to be in suitable form and may be raw or chemically activated clay catalysts of the bentonite or kaolin type, or synthetically produced gels containing silica in admixture with one or more of the refractory oxides of aluminum, thorium, zirconium, magnesium, uranium, beryllium and the like. Other synthetic colloidal masses such as phosphates of zirconium, cerium, thorium and the like may be used. In any event, the utility of a cracking catalyst may be evaluated by a standardized activity test and it is preferred, in the

present invention, to use catalysts of moderate or high activity, such as catalysts having activities of greater than 25 and preferably above 30.

The activity test mentioned above is a standardized test for the characterization and control of cracking catalysts and is used by a number of industrial laboratories. It is known as the "CAT-A" test and is described in "Laboratory Method for Determining the Activity of Cracking Catalysts" by J. Alexander and H. G. Shimp, page R-537, National Petroleum News, August 2, 1944. In accordance with the method, a standardized light gas oil is subjected to contact with a static bed of the catalyst to be tested under standard cracking conditions of atmospheric pressure, 800° F. and a rate of oil flow of 1.5 volumes of liquid oil per volume of catalyst per hour. The cracked products are collected and analyzed to obtain the activity index, or "CAT-A" activity, which is the volume of motor gasoline produced divided by the volume of charge stock times 100. The weight per cent of the uncondensed gas and coke (carbonaceous deposit) as well as the specific gravity of the gas are also determined.

The above described test is used to evaluate the effect of severe process or accelerated conditions; thus, the activity of a sample of a catalyst which has been calcined using no steam, at 1050° F. in flowing dry air for two hours (hereafter designated as a dry calcination), may be compared with the activity of a sample of the same catalyst which has been calcined in the presence of a high partial pressure of steam at elevated temperatures as, for example, at 1350° F. for four hours using about 15 pounds per square inch absolute pressure of steam (hereafter designated as a steam calcination). Evaluations of the effect of process conditions based on the above and similar calcinations have been compared with data on commercial catalysts which have been in commercial use for many months or even years and the comparison shows that these calcinations can be used to measure the relative effect on cracking catalysts of prolonged exposure at temperatures of 700° to 1500° F. to the quantities of steam encountered in commercial cracking operations.

Multicomponent refractory oxide cracking catalysts, such as silica-alumina catalysts, which show less than a 50% reduction in "CAT-A" activity between samples subjected to the above described dry and steam calcinations based on the first named sample (i. e., 100 times the activity of the dry calcined sample minus the activity of the steam calcined sample divided by the activity of the dry calcined sample) are considered to be steam resistant and have a satisfactory commercial life when regenerated according to the present invention. As an example of the effect of the coke deposit, a catalyst which showed a reduction of about 25% in activity between dry and steam calcined samples showed a reduction of only about 13% when the catalyst used for the steam calcination had a deposit of coke, at the start of the calcination amounting to 16 grams per liter. Similar results have been obtained for different amounts of coke deposit and for different process conditions.

Many of the advantages of the present invention may be realized in an embodiment thereof in which the catalyst is protected during a portion of the cracking period when deactivating amounts of steam are present by contacting the catalyst prior to such a portion of the cracking period with hydrocarbons under cracking conditions selected to provide a protective amount of

coke deposit. Thus, in the first portion of the cracking period, the cracking catalyst, which is preferably of moderate or high activity, is contacted in a first cracking zone with a relatively low boiling charge stock, which preferably completely volatilizes substantially at the temperature of cracking without the aid of steam, and a protective amount of coke, such as an amount greater than 15 grams per liter, thereby deposited on the catalyst. The catalyst is thereafter immediately contacted in a second cracking zone with a relatively high boiling charge stock in the presence of deactivating partial pressures of steam, the steam being used to aid in the volatilization of the charge stock. If the relatively high boiling stock is sufficiently easily cracked, the cracking conditions in the first and second cracking zones, which zones may be in the same or different reactors, may be essentially the same. However, if advantageous, conditions in the second zone may be made more severe by increasing the temperature as by mixing catalyst from the first zone with hot partially regenerated catalyst having a protective coke deposit thereon. Other methods, such as increasing the pressure or decreasing the space velocity or increasing the catalyst to oil ratio, may also be employed for increasing the severity of cracking. After passage through the second zone, the catalyst may be regenerated wholly or partially, such as being regenerated until 4 to 6 grams per liter of deposit remain, and thereafter reused in the same process. By this process, the useful life of the catalyst is prolonged by the protective effect of the coke deposit during both the cracking and regeneration periods, while a high yield of cracked products are obtained from various fractions of a crude oil, such fractions having different boiling ranges, by cranking each of these fractions under cracking conditions selected to give the optimum yields for such fraction. By this process, the beneficial effect of steam in the volatilization of charge stocks may be utilized while minimizing or avoiding the deleterious effect of steam on the catalyst.

In order to understand the invention more fully, reference should be had to the drawing which illustrates an embodiment of the present invention, which invention is not, however, limited in scope thereto. Fig. 1 is a schematic flow diagram in which details of conventional auxiliary equipment have been omitted for clarity and which will be described in connection with operations in which a fluent refractory contact mass is cyclically circulated in a system known as the "T. C. C." system. Details of this system, as applied to cracking operations, have been described in various published articles (see, for example, "The T. C. C. Catalytic Cracking Process for Motor Gasoline Production" by R. H. Newton, G. S. Dunham, and T. P. Simpson, Transactions of the American Institute of Chemical Engineers, volume 41, page 215, April 25, 1945, and the articles there cited) and hence will not be repeated here. Although the drawings exemplify one type of moving contact mass operation, the present invention can be embodied in other types of operations which use fluent solid contact masses or may be embodied in that type of operation known as fixed bed operation.

In Fig. 1 a cracking catalyst, such as a low-alkali content silica-alumina gel having a mol ratio of silica to alumina of between about 5 to 1 and 15 to 1, is fed from hopper 5 by catalyst leg 6 to reactor 7 where the catalyst is contacted

with a light charge stock, such as a virgin or cracked naphtha or gas oil having a dew point at atmospheric pressure below the temperature of cracking in reactor 7, the light charge stock being introduced to the reactor by line 8 after having been previously vaporized. The catalyst, as introduced to reactor 7, is preferably a high activity catalyst, such as a catalyst having a "CAT-A" activity of greater than 30 and preferably greater than 35, and preferably has a low coke deposit, such as less than 4 to 6 grams per liter, such as 2 to 4 grams per liter. The charge stock is cracked by subjecting it to cracking conditions such that at least 35 and preferably 40 or more volume per cent of gasoline based on the charge stock is produced. Such cracking conditions are generally included in the ranges of 800° to 950° F.; atmospheric and higher pressures up to 100 pounds per square inch; ratios of the liquid volume of charge stock charged per hour to bulk volume of catalyst circulated per hour of 0.1 to 10 and space velocities (ratio of the liquid volume of the charge stock charged to the reactor per hour to bulk volume of catalyst in cracking zone) of 0.1 to 5.0. Alternatively, the charge stock may be a virgin or cracked gasoline, which is reformed to yield a high octane gasoline, such as a gasoline of over 70 octane number. In any event, the catalyst accumulates a protective coke deposit by remaining in the reactor for a length of time (which is called the residence time) such that, under the cracking conditions employed in reactor 7, the catalyst accumulates a deposit greater than about 15 grams per liter but generally less than 25 grams per liter. The catalyst is then conveyed by line 11 to reactor 9 where it is contacted with a relatively high boiling charge stock, such as a hydrocarbon fraction having a dew point of over 800° F. as, for example, a crude residuum from which the tar has been removed. The relatively high boiling charge stock, which is introduced to reactor 9 by line 12 after having been heated to a suitable temperature, is admixed with high temperature steam from line 13 in order that the steam may aid in the volatilization of the charge stock. The charge stock, which is preferably substantially completely in the vapor phase as it enters reactor 9, passes upward through reactor 9 and is at least partially cracked by contact with the downwardly moving catalyst. The cracked charge stock or synthetic crude is removed from reactor 9 by line 14 and conveyed to a fractionation system for the separation of various products such as gasoline, solvent naphtha, fuel oil, recycle gas oil and the like. In a similar fashion, synthetic crude from reactor 7 is conveyed to the same or a similar fractionation system by line 15 for similar treatment.

The temperature of the catalyst in reactor 9 may be increased above the temperature of the catalyst in line 11 by mixing the catalyst from reactor 7 with catalyst from line 16, which catalyst has been partially regenerated in regenerator 17 and thereby increased in temperature. The amount of catalyst from line 16 used in reactor 9 will depend on the relationship of the temperatures in reactor 7, regenerator 17 and reactor 9 but it is generally preferred to use an amount of catalyst such that the temperature of reactor 9 is raised so as to produce at least 30 and preferably over 35 volume per cent of gasoline from the charge stock. The temperature rise of the catalyst from reactor 7 will generally be of the order of 50° to 150° F. In this manner, heat

produced as a result of the regeneration of the coked catalyst is utilized in connection with the cracking operation and serves to balance the endothermic effect of the latter. The catalyst in line 16 has been preferably regenerated so that the coke deposit thereon is about equal to that on the catalyst in line 11 (i. e., about 15 to 25 grams per liter) and is thereby likewise protected against the steam encountered in reactor 9 in which reactor the steam concentration may range from 5 to 20 parts by weight of steam to 100 parts of oil at 1 to 2 atmospheres or slightly higher total pressure (i. e., a range of 6 to 20 pounds per square inch partial pressure of steam). By maintaining at least 10 grams per liter of coke on the catalyst and preferably 15 grams per liter or more if the partial pressure of the steam is above 10 pounds per square inch, the deactivating effect of the steam present in the reactor is diminished. Thus, for example, a catalyst subjected to 15 pounds per square inch partial pressure of steam at 900° F. has 2 or more times the life (for the same reduction in "CAT-A" activity) when it is protected with 15 grams per liter of coke than it does when the amount of coke is maintained at the usual level of 4 to 6 grams per liter.

The catalyst, which after passage through reactor 9, has a coke deposit totaling preferably at least 25 and generally about 30 to 40 grams per liter or higher, is removed from reactor 9 by line 18, and conveyed to elevator 19 which carries the catalyst to line 21 and thence to hopper 22. The catalyst is fed from hopper 22 by line 23 to regenerator 17 which may be a "T. C. C." kiln comprising a plurality of burning and cooling sections or zones (two of which are shown in regenerator 17). A controlled amount of air from manifold 24 burns some of the coke deposit in each section of the kiln, the spent flue gases being removed by manifold 25. Excess heat generated by combustion of the coke deposit is removed by indirect heat exchange, using cooling coils 26. The conditions of combustion in regenerator 17 and the temperature of the air used therein are selected so that the heat of combustion soon raises the temperature of the catalyst to greater than 1100° F., such as a temperature in the range of 1200° to 1350° F. The safe temperature of combustion is dependent on the amount of the coke deposit on the catalyst as introduced to the regenerator, and the lower temperatures, such as about 1200° F., are preferred when the amount of the coke deposit is about 30 grams per liter whereas higher temperatures, such as 1300° or higher, may be employed when the coke deposit is in excess of 40 grams per liter.

The catalyst, after partial regeneration, may be conveyed from regenerator 17 by line 27 to regenerator 28, which is similar in design to regenerator 17, and additional regeneration effected. Alternatively, a single regenerator with appropriate arrangements for the draw off of catalyst may be used. As noted above, the hydrogen of the coke burns preferentially in the early stages of combustion and hence the content of steam in the flue gases diminishes more rapidly than the protective effect of the remaining coke deposit. The temperature of regeneration in regenerator 28 may therefore be higher than that of regenerator 17 but, in all instances should be below the temperature of thermal deactivation for the particular type of catalyst employed.

The temperature of thermal deactivation of a catalyst is the temperature above which rapid deactivation occurs in a non-deleterious atmos-

phere, such temperatures being, for example, about 1500° F. for clay catalysts and about 1700° F. for synthetic silica-alumina catalysts. In general, the same temperature of regeneration in both regenerators is correlated with the amount of protective coke deposit and the partial pressure of steam. It has been found by investigation that steam resistant catalysts (as defined above) will have a satisfactory commercial life when the minimum amounts of coke given in the table are observed at the stated partial pressures of steam.

Table

Temp.	Amount of	Partial	Amount of	Partial	Amount of	Partial
	grams per liter	lbs./sq. inch	grams per liter	lbs./sq. inch	grams per liter	lbs./sq. inch
1,150° F.			10	3.9	18	4.4
1,200° F.	15	1.5	18	3.9	23	4.4
1,300° F.	23	1.5	26	3.9	30	4.4
1,350° F.	30	1.5				

It is, however, preferred, according to the invention, to have the minimum coke about 25% higher than the values given in the table to provide a factor of safety and to allow for the reduction of the coke deposit during the regeneration.

The catalyst, after being regenerated so as to leave a predetermined residue of coke deposit thereon, is removed from regenerator 28 by line 29, conveyed by elevator 31 to line 32 and thence charged to hopper 5 from which it may be removed for reuse.

In another embodiment of the invention, a very high boiling charge stock, such as a residuum having an end boiling point of greater than 1100° F. and a mid boiling point between 800° to 1100° F. at atmospheric pressure is charged in a mixed phase condition to a cracking catalyst having a protective coke deposit, the catalyst being at a temperature generally higher than vapor phase operations, such as temperatures in a range of 900° to 1100° F. Typical charge stocks employed in such mixed phase operations are commonly admixed with about 5 to 10 parts by weight of steam to 100 parts of charge stock prior to the heating of the charge stock to the temperature of introduction to the cracking zone, generally about 700° to 950° F., in order to prevent coking of the charge stock in the tube stills used for heating. The deactivating effect of the steam admixed with the charge stock (which, for the operation described above, amounts to partial pressures of from about 7.0 to 10.0 pounds per square inch) at the temperatures of the cracking operation (900° to 1100° F.) may be decreased by employing a relatively active cracking catalyst, such as a catalyst having a "CAT-A" activity of at least 30 and preferably at above 35, which catalyst has a coke deposit amounting to at least 15 grams per liter and preferably in the range of 20 to 30 grams per liter at the start of the cracking operation. When a catalyst is used which is originally so active that, under the cracking conditions employed in the process, overcracking would result (i. e., overcracking is the formation of gas and coke at the expense of gasoline formation), the coke deposit decreases the activity of the catalyst and thus decreases overcracking while protecting the catalyst against the deactivating effect of steam. The catalyst, after use in the mixed phase cracking operation generally has a coke deposit amounting to 30 to 50 grams per liter, which, as discussed above,

protects the catalyst in the subsequent regeneration. The catalyst from the mixed phase operation may be partially regenerated so as to leave a coke deposit of at least 15 grams per liter and thereafter reused in the mixed phase cracking operation.

After extended periods of use, most catalysts are unavoidably aged. In this event, the amount of the coke deposit maintained during the cracking period may be decreased with a consequent increase in the catalytic activity. Thus, in a commercial process operated continuously, by start-

ing with an over active catalyst on which sufficient coke is maintained during both the cracking and regeneration phases so as to decrease the aging effect of steam present during these and other process periods, the useful life of the catalyst can be extended, particularly when the amount of coke maintained on the catalyst during the cracking period is reduced as the aging of the catalyst proceeds.

It is to be understood that where the term, partial pressure of steam, is used that such an expression includes those instances where steam is essentially the only vaporous material present and the partial pressure of steam is hence equal to the total or absolute pressure of the system.

Obviously many modifications and variations of the invention as hereinbefore set forth may be made without departing from the spirit and scope thereof and therefore only such limitations should be imposed as are indicated in the appended claims.

I claim as my invention:

1. In a catalytic cracking system in which fluent solid cracking catalysts contacts substantially only hydrocarbons in a first stage cracking operation and contacts hydrocarbons and substantial amounts of steam in a second stage cracking operation, the improvement which comprises maintaining cracking conditions in said first stage cracking operation so as to deposit an amount of coke on substantially completely regenerated catalyst sufficient to furnish substantial protection to said catalyst against the deactivating effect of steam in said second stage, contacting a mixture of catalyst from said first stage and partially regenerated catalyst comprising an amount of coke at least equal to the coke on said catalyst from the first stage with hydrocarbons in the presence of a deactivating partial pressure of steam in said second stage and thereby depositing additional amounts of coke on said mixture of catalyst, partially regenerating catalyst from said second stage cracking operation so as to produce catalyst comprising an amount of coke at least equal to the amount of coke produced in said first stage cracking operation, introducing a portion of said partially regenerated catalyst to said second stage cracking operation, further regenerating another portion of said partially regenerated catalyst so as to produce substantially completely regenerated catalyst and introducing

substantially completely regenerated catalyst to said first stage cracking operation.

2. In a catalytic cracking system in which fluent solid cracking catalyst contacts substantially only hydrocarbons in a first stage cracking operation and contacts hydrocarbons and substantial amounts of steam in a second stage cracking operation, the improvement which comprises maintaining cracking conditions in said first stage cracking operation so as to deposit an amount of coke on substantially completely regenerated catalyst sufficient to furnish substantial protection to said catalyst against the deactivating effect of steam in said second stage, contacting a mixture of catalyst from said first stage and partially regenerated catalyst comprising an amount of coke at least equal to the coke on said catalyst from the first stage with hydrocarbons in the presence of a deactivating partial pressure of steam in said second stage under such conditions as to deposit an amount of coke on said catalyst sufficient to furnish substantial protection to said catalyst during that portion of the subsequent regeneration when said catalyst is contacted with deactivating partial pressures of steam, partially regenerating catalyst from said second stage cracking operation at temperatures of at least 1200° F. under conditions such that the coke deposit that remains on said catalyst is at least as much as the coke deposit on the catalyst from said first stage operation, introducing a portion of the partially regenerated catalyst to said second stage cracking operation, further regenerating a portion of the partially regenerated catalyst at temperatures of at least 1200° F. so as to produce substantially completely regenerated catalyst and introducing substantially completely regenerated catalyst to said first stage cracking operation.

3. In a catalytic cracking system in which fluent solid siliceous cracking catalyst contacts substantially only hydrocarbons in a first stage cracking operation and contacts hydrocarbons and substantial amounts of steam in a second stage cracking operation, the improvement which comprises maintaining cracking conditions in said first stage cracking operation so as to deposit coke to the extent of at least 15 grams of carbon per liter of catalyst on substantially completely regenerated catalyst having a deposit of less than 6 grams of carbon per liter of catalyst, contacting a mixture of catalyst from said first stage and partially regenerated catalyst comprising an amount of coke at least equal to the coke on said catalyst from the first stage with hydrocarbons in the presence of a deactivating partial pressure of steam in said second stage under such cracking conditions as to deposit an amount of coke on said catalyst sufficient to provide at least 15 grams of carbon per liter of catalyst on said catalyst during that portion of the subsequent regeneration when said catalyst is contacted with a partial pressure of steam of more than 0.8 pound per square inch, partially regenerating catalyst from said second stage cracking operation at temperatures of at least 1200° F. under conditions such that a deposit of coke of more than 15 grams of carbon per liter of catalyst remains on said catalyst, introducing a portion of the partially regenerated catalyst to said second stage cracking operation, further regenerating a portion of the partially regenerated catalyst at temperatures of at least 1200° F. so as to produce substantially completely regenerated catalyst having a coke deposit of less than 6 grams of carbon per

liter of catalyst and introducing substantially completely regenerated catalyst to said first stage cracking operation.

4. In the catalytic conversion of hydrocarbons using solid hydrocarbon conversion catalyst, which catalyst is employed in a cyclic process comprising a conversion period and a regeneration period, during which conversion period hydrocarbons contact said catalyst to form conversion products and concomitantly deposit coke on said catalyst and during which regeneration period the coked catalyst is regenerated by contacting it with oxygen containing gas under combustion conditions so as to remove at least a portion of said coke with the consequent presence of steam in the flue gases present during the regeneration, the steps which comprise contacting said catalyst with hydrocarbons during said conversion period and depositing a protective amount of coke on said catalyst sufficient to provide a deposit of at least 15 grams of carbon per liter of catalyst during the subsequent regeneration period until the partial pressure of steam in the flue gases is less than about 0.8 pound per square inch, contacting catalyst comprising said protective amount of coke with oxygen containing gas in a first regeneration zone, effecting an initial partial regeneration of said catalyst in said first regeneration zone at temperatures of at least 1200° F. and generating flue gases having a partial pressure of steam therein of greater than 0.8 pound per square inch, separating said partially regenerated catalyst and flue gases, contacting said partially regenerated catalyst with additional oxygen containing gas in a second regeneration zone, completing regeneration of said partially regenerated catalyst in said second regeneration zone at temperatures of at least 1200° F. and under conditions such that the partial pressure of steam in the gases present is less than 0.8 pound per square inch and thereafter contacting completely regenerated catalyst with hydrocarbons under conversion conditions.

5. In the catalytic cracking of hydrocarbons using solid hydrocarbon cracking catalyst, which catalyst is employed in a cyclic process comprising a cracking period and a regeneration period, during which cracking period hydrocarbons contact said catalyst to form cracked products and concomitantly deposit coke on said catalyst and during which regeneration period the coked catalyst is regenerated by contacting it with oxygen containing gas under combustion conditions so as to remove at least a portion of said coke with the consequent presence of steam in the flue gases present during the regeneration, the steps which comprise contacting said catalyst with hydrocarbons during said cracking period and depositing a protective amount of coke on said catalyst sufficient to provide a deposit of at least 30 grams of carbon per liter of catalyst during the subsequent regeneration period until the partial pressure of steam in the gases present is less than about 1.5 pounds per square inch, contacting catalyst comprising said protective amount of coke with an oxygen containing gas in a first regeneration zone, effecting an initial partial regeneration of said catalyst in said first regeneration zone at temperatures of at least 1200° F. and generating flue gases having a partial pressure of steam therein of greater than 1.5 pounds per square inch, separating said partially regenerated catalyst and flue gases, contacting said partially regenerated catalyst with additional oxygen containing gas in a second regen-

eration zone, completing regeneration of said partially regenerated catalyst at temperatures of at least 1200° F. and under conditions such that the partial pressure of steam in the gases present is less than 1.5 pounds per square inch and thereafter contacting catalyst so regenerated with hydrocarbons under cracking conditions.

6. In the catalytic cracking of hydrocarbons using solid cracking catalyst, which catalyst is employed in a process comprising a cracking period and a regeneration period, during which cracking period hydrocarbons contact said catalyst to form cracked products and concomitantly deposit coke on said catalyst, during which regeneration period an oxidizing gas contacts said catalyst under combustion conditions so as to remove at least a portion of said coke, the steps which comprise contacting substantially completely regenerated catalyst having a deposit of less than 6 grams of carbon per liter of catalyst with substantially only relatively light hydrocarbons having a dew point below the temperature of cracking in a first cracking operation and depositing coke on said catalyst such that the total amount of coke on the catalyst after said first cracking operation totals at least 15 grams of carbon per liter of catalyst, and thereafter contacting said catalyst comprising at least 15 grams of carbon per liter of catalyst with a gaseous mixture of relatively heavy hydrocarbons having a dew point of over 800° F. and steam, said steam having a partial pressure of at least 6 pounds per square inch, in a second cracking operation.

7. In a process for the catalytic cracking of hydrocarbons using solid cracking catalyst, the steps which comprise contacting substantially completely regenerated catalyst having a deposit of less than 6 grams of carbon per liter of catalyst with substantially only relatively light hydrocarbons having a dew point below the temperature of cracking in a first cracking operation and depositing coke on said catalyst such

that the total amount of coke on the catalyst after said first cracking operation totals at least 15 grams of carbon per liter of catalyst, contacting said catalyst comprising at least 15 grams of carbon per liter of catalyst with a mixture of relatively heavy hydrocarbons having a dew point of over 800° F. and steam, said steam having a partial pressure of at least 6 pounds per square inch, in a second cracking operation, contacting catalyst from said second cracking operation with oxygen containing gas in a first regeneration zone, effecting an initial partial regeneration of said catalyst in said first regeneration zone at temperatures of at least 1200° F. and generating flue gases having a partial pressure of steam of greater than 0.8 pound per square inch, separating said partially regenerated catalyst and flue gases, contacting said partially regenerated catalyst with additional oxygen containing gas in a second regeneration zone and completing regeneration of said partially regenerated catalyst in said second regeneration zone at temperatures of at least 1200° F. and under conditions such that the partial pressure of steam in the gases present is less than 0.8 pound per square inch.
